UNITED STATES PATENT OFFICE.

JUSTIN PARMELEE, OF CHICAGO, ILLINOIS.

ART OF MOLDING.

SPECIFICATION forming part of Letters Patent No. 366,869, dated July 19, 1887.

Application filed December 13, 1886. Serial No. 221,437. (No model.)

To all whom it may concern:

Be it known that I, JUSTIN PARMELEE, of Chicago, in the county of Cook and State of Illinois, have invented new and useful Improvements in the Art of Molding; and I do hereby declare that the following is a full, clear, and exact description thereof, reference being had to the accompanying drawings, making part of this application.

10 My invention relates to the art of molding; and it consists in a new and useful improvement therein, which will be found hereinafter more fully explained, and which will be made the subject of the claim of this specification, in 15 which claim my said improvement will be found specifically pointed out and clearly defined.

In order to fully explain the nature or character of my improvement and the difference 20 between the mode which I have devised and that heretofore practiced, I deem it desirable and necessary to first explain, briefly, the mode heretofore usually practiced for producing molds in sand for the casting of tubular and 25 other hollow articles—such as pipe fittings, elbows, &c.—in making which green-sand cores are used, and to which my invention more especially relates.

Taking, for illustration, the making of a 30 mold in sand for the casting of a pipe elbow or connection, the heretofore-practiced mode of producing the mold has been about as follows, namely:

The molder, having taken two “follow- 35 boards” and placed within a cavity or aperture in each one a half-pattern of the article to be produced, (the pattern generally being made of metal,) first proceeds to fill in the pattern with sand, which also enters into and fills 40 the depressions or curved cavities in the faces of the follow-boards, the lowermost adjacent portions of which cavities coincide with the hollowed-out end portions of the metallic patterns, a core-arbor (usually of metal) having 45 been properly arranged within one of the patterns with its ends projecting into the said cavities or depressions that are formed in the face of one of the follow-boards, after which the properly-rammed sand is struck off in a 50 manner well understood. These operations leave the two half-patterns in the two follow-

boards, with the sand core formed in halves in the said patterns respectively, and with the protruding ends of each half of said core supported within the depressions or cavities 55 formed (as above mentioned) in said boards. The two follow-boards are next placed together face to face, with that one containing the core-arbor preferably beneath the other, and the topmost follow-board is then removed, 60 leaving the metallic half-pattern that was in it, and also that half of the sand core which had been formed within said half-pattern, resting properly in place upon the half-pattern and half-core of the remaining or lower follow-board, those portions of the upper half of 65 the sand core which project beyond the upper half-pattern now coinciding with and resting upon the similar projections of the lower half of the sand core, that is supported by and that 70 is still within the other half-pattern and lower follow-board. The exposed uppermost half-pattern is then “rapped down” in the usual manner to perfect the cylindricity of the core, (by forcing the adjacent edges of the metallic 75 patterns into contact,) after which the projecting ends of the upper half of the sand core are smoothed up and hardened by hand-pressure in the manner well understood by those skilled in the art. This is called “making a 80 parting,” and after this the brush and bellows are successively used in a manner well known to clean off the top of the follow-board, and to also remove any sand from the angles and crevices of the exposed pattern, after 85 which the projecting end portions of the upper half of the sand core are sprinkled with “parting sand,” any superfluity of which is blown off from the top of the follow-board and from the angles and crevices in the usual manner. 90 A half-flask is now put on top of this follow-board and is filled in with sand (a sprue-stick having been inserted with its upper end projecting up to nearly the top of the flask) and the sand is thoroughly rammed in and struck 95 off. As usual, in ramming the sand a rammer is used, (provided with both a peen and a butt, like a hammer,) the peen portion being used to ram in around the edges of the pattern and flask, while the butt is employed 100 to ram down the middle portion of the sand. A “roll-over board” is then laid upon the

top of this filled half-flask or half-mold, after which the said flask, together with the roll-over board and the follow-board beneath, are turned upside down on the floor or ground 5 and the follow-board then taken off, leaving exposed the surface of the sand in the half-flask surrounding the pattern, also the end portions of the completed core of sand and the half-pattern that originally laid in said follow-board. All surplus sand is then removed and the projecting ends of the core are smoothed up and hardened by hand, (to insure a "lift,") after which the top of the sand is leveled off and hardened round about the edges of the 15 metallic pattern (usually with a trowel) in order to make a good hard parting, after all of which the top of the sand is brushed and blown off clean. Then parting sand is applied to the whole sand surface, including the exposed end 20 portions of the sand core, and all superfluity of parting sand having been blown out of the crevices and off of the metallic half-pattern, (so as to avoid any roughening of the surface of the molds to be yet made from said half-pattern,) another half-flask is put on top and is filled in with sand and rammed, as in the case of filling the previous half-flask, and the sand is then struck off, thus completing the 25 other half of the mold. Then a bottom board is put on top of this last-filled half-flask, and, having been settled down into perfect contact with the upper edges of the flask, said bottom board and top flask are then turned over or removed, and the half-pattern therein is then 30 rapped and taken off, thus exposing the lower half of the core and its arbor. The two half-flasks are then closed together and the bottom board put on, (without rubbing down to a bearing,) and the whole is turned over again, or 35 upside down, for the purpose of the removal of the rolling-board, after which the sprue-stick is taken out and the sprue-hole fixed, when the top half-flask is removed and the remaining half-pattern taken away from it, the 40 gate to the sprue formed, and the mold finished up with a slicker. After this the usual sprinkling with water is done to hold the sand securely together at the edges of the walls of the mold; and after having blown out the mold 45 beneath the core and cleaned out the sprue the half-flasks are again put together and the mold is ready for the pouring of the metal to make the casting.

As is well understood by those familiar with 50 the art of molding in thus practicing it according to the mode heretofore known, the method is such that the sand core is made first (within the metallic pattern-pieces) and the protruding or projecting end portions of 55 said sand core are formed within the seats or depressions (made for the purpose) in the follow-boards, and when the flasks come to be subsequently filled and rammed with sand to produce the two halves of the mold proper this 60 filling in and ramming down of the sand in the flasks has to be done on top of the exposed end portions of the sand core, and in the perform-

ance of these operations, even by experienced and skillful molders, there is always more or less liability or danger of "breaking down" 70 or spoiling these exposed end portions of the core, the result of which is a greater or less mutilation of the mold (in the sand) that is relied upon for the production of a perfect casting and an exact duplicate of the pattern from 75 which the mold is made. I propose by my invention to overcome entirely this serious objection, and in order to accomplish this desirable end I have devised and put into practical operation a mode or method of producing the 80 molds, in which the two halves of the mold proper are formed before the making of the core, and in which, during all the operations of filling and ramming in sand, (to make both the mold proper and the core,) the sand employed 85 never has to be filled in and rammed down on a sand surface that constitutes a portion of either the mold or the core.

To enable those skilled in the art to understand and practice my invention, I will now 90 proceed to more fully explain it as compared with the foregoing general description of the old-fashioned method of molding, and to render the description of my improvement in the art more explicit I will refer by letters of reference to the accompanying drawings, which form a part of this specification, and in which I have shown an apparatus or appliances adapted to the carrying into effect of my improved mode of molding, and which are made 95 like those which I have so far used in practicing my said invention.

In the drawings the different figures and parts hereinafter alluded to illustrate both the devices or apparatus which I employ in carrying on my mode of molding, and also the successive operations or steps which are necessary to my said improvement in the art, as I will now proceed to explain.

Figure 1 is a perspective view of the follow-board and half-pattern; Fig. 2, the same with the cope applied; Fig. 3, the same as Fig. 2, filled with sand; Fig. 4, the same as Fig. 3 with a rolling-board applied; Fig. 5, a view of the cope inverted, the follow-board having been removed; Fig. 6, the same as Fig. 5, the hollow half-pattern having been filled with sand; Fig. 7, a view of the drag, half-pattern, and core-bar, the drag being filled with sand and the parts in the same relative position as in Fig. 6; Fig. 8, a view of the cope with the drag placed thereon; Fig. 9, a view of the cope after the removal of the drag; Fig. 10, the same as Fig. 9, with the half-pattern removed; Fig. 11, a view of the completed mold.

In practicing my invention I take a follow-board, such as seen at A, and which is simply formed or provided with a plane surface to properly support a half-pattern—such as seen, for instance, at B—in the position illustrated at Fig. 1, and having placed said half-pattern on said follow-board in the position illustrated, I next place on said follow-board a half-metallic flask, C, in the position seen at Fig. 2, and

then fill said flask with sand, which is rammed in in the usual manner and then struck off and sprinkled over, all as shown at Fig. 3. After this a plain rolling-board, I, is laid on top 5 of the filled flask, (see Fig. 4,) and the said rolling-board, the filled flask, and follow-board (with its half-pattern) are then all turned over, or upside down and the said follow-board removed, leaving the half-pattern embedded 10 in the sand of said half-flask, (with the concave surface of the pattern uppermost,) the top edges of the metallic pattern being flush with the edges or on a level with the top edges of said half-flask, all as illustrated at Fig. 5. 15 As will be seen from said last-mentioned figure, the half metallic flask C is formed or provided with semi-cylindrical inwardly-projecting flanges c, which very nearly meet and which coincide with the semi-cylindrical edges 20 at the ends of the half shell or metallic pattern B, so that when sand shall be filled in (as is next to be done) to fill up the interior of said metallic pattern to make the first half of the core, as illustrated at Fig. 6, said sand will be 25 supported at all points by either the said metallic pattern or these semi-cylindrical metallic projections c of the metallic half-flask. After the sand shall have been filled in to form one half of the core, as shown at Fig. 6, the 30 sand is "struck off" in the usual manner, the half-pattern having been first rapped, however, so as to subsequently get a better lift, (which is not possible in the old mode because the core always is in the half-pattern when the 35 first opportunity occurs to get at the edge of the latter,) and the half-core and half-mold thus formed are then set one side.

It will be understood that there are register-pins p in the follow-board A and in the said 40 half-flask that are arranged to register with pins in the second follow-board and with the other half-flask.

The above-described operations are now repeated (with duplicate appliances) and with 45 the other half of the pattern, except that an ordinary core-arbor, E, is applied in connection with the other half, B', of the pattern, all as fully shown at Fig. 7, and in moving this last-mentioned flask and placing it on the top 50 of the other, as seen at Fig. 8, the ends of the core-arbor E are held up by the fingers of the operator, thus preventing any "drop" of the core and also holding the metallic pattern securely up in place. Now, the top half, C', of 55 the flask (see Fig. 8) is lifted off and put one side, thus exposing the upper one, B', of the two half-patterns, as seen at Fig. 9, which half-pattern B' is then rapped and lifted off, as shown by Fig. 10. After this the half-flask 60 C' is put back into its former relationship with the other flask, (see Fig. 8,) and after the application to its top of a rolling-board, I', the combined parts or appliances are all rolled over, or turned upside down, and the board I 65 removed, when, with a sprue-cutter or hollow tube a hole is made down to the metal gate, (formed on the remaining half of the pattern.)

as clearly shown at Fig. 11, and the other half-flask, C, is lifted off and the other half-pattern, B, is removed (with its gate) after having been 70 properly rapped. The edges of the wall of the mold are then wetted and the well-hole is blown out, after which the flasks are reunitied or put back into the condition seen at Fig. 11, ready 75 for pouring. In putting the parts of the flasks together they are fastened by ordinary clamping devices—such as seen at e—after which the usual steady-pins are knocked out.

Now, it will be observed that in proceeding 80 as above described, with appliances such as I have illustrated and have herein alluded to, there never is any ramming of sand against sand to distort any of the parts of either the mold proper or the sand core, and that, therefore, in the use of my improved mode, by the 85 employment of appliances (or a contrivance) substantially such as shown and described, the molding operations can be performed with perfect success by comparatively unskilled hands. 90

It is important that the semi-cylindrical metallic projections c of the metallic flasks should be made and arranged so that the ends which are adjacent to the metallic half-patterns (when the latter are placed in the proper position on the follow-board) should not come into contact with said pattern, in order that a thin layer or stratum of sand shall always lie intermediate of these ends of these semi-cylindrical projections and the wall of the mold 100 against which the hot metal is to come in pouring, and from which the casting is to receive its shape.

Of course appliances more or less different 105 in the details of construction from those I have herein shown and described may be devised and employed for the purpose of carrying out my improvement in the art of molding, although the appliances which I have shown I 110 have found to give perfect satisfaction in practical operation, and they constitute the subject-matter of another application for Letters Patent by me (No. 221,438, filed December 13, 1886) on the apparatus or appliance for carrying into effect the improvement in the art 115 made the subject of this case.

Not only am I enabled by my present invention to avoid all liability of those imperfections 120 in the finished casting which are so apt to arise under the mode of producing the molds heretofore employed, but I am furthermore enabled to produce the molds for the making of perfect castings without the use of skilled labor, and thus at very much less expense 125 than it has heretofore been possible to accomplish such results.

Having now so fully explained my invention as to enable those skilled in the art to easily distinguish between my improvement in the art of molding and said art as heretofore practiced, and to use my improvement, what I claim as new, and desire to secure by Letters Patent, is— 130

As an improvement in the art of making

sand molds for cored articles, first making the half-molds from the metallic or other patterns, and subsequently making the halves of the sand core within the patterns in the half-flasks, then uniting the halves of the core and closing the flasks containing the half-molds, (after the removal of the patterns,) all substantially in the manner hereinbefore explained, whereby I avoid, during the formation of the mold and core, the filling in or

ramming in of the sand for any of the parts of the mold against the sand composing any other portion of the mold or its core.

In witness whereof I have hereunto set my hand this 28th day of October, 1886.

JUSTIN PARMELEE.

In presence of—

JNO. WETFORD,
W. S. VERITY, Jr.
